UNITED STATES PATENT OFFICE

JOSEPH A. SICKELS, OF KANSAS CITY, MISSOURI

SAFETY CUT-OFF DEVICE FOR GAS SERVICE

Application filed May 31, 1930. Serial No. 458,130.

This invention relates to safety cut-off device for gas service and has for its principal object the provision of a thermostatic bar controlled by a flame supplied with gas from the distributing pipe which controls a switch of an electric circuit by means of which a control valve is closed when the thermostatic bar cools due to the cutting off of the supply of gas to the flame.

10 A further object of the present invention is the provision of a novel means for maintaining the control valve in the open position when the electric circuit is maintained open due to the action of a flame heating a thermostatic bar.

Another object of this invention is to provide a safety cut-off device that may be positioned remote from the gas burner or the service device which consumes the gas.

20 With these general objects in view as well as minor objects which will appear during the course of the detailed specification, reference will now be made to the accompanying drawing in which:

25 Figure 1 is a side elevation, partly broken away, of a gas service equipped with a safety cut-off device embodying this invention;

Fig. 2 is a plan view of the parts shown in Fig. 1;

30 Fig. 3 is a fragmentary sectional view taken on line III—III of Fig. 2;

Fig. 4 is a fragmentary sectional view taken on line IV—IV of Fig. 2;

35 Fig. 5 is a diagrammatic view of the electric circuit by means of which the supply control valve is controlled.

40 Like reference characters designate similar parts throughout the several views and the numeral 10 designates a supply pipe which communicates with any suitable gas supply not shown, and 11 is a control valve for the supply pipe to which is attached a distributing pipe 12. This distributing pipe conducts the gas to the burner 13 or any other service device where the gas is consumed.

45 Whenever the valve 11 is in the open position the distributing pipe will be filled with gas as long as the flow of gas in the supply pipe is not interrupted. Should the supply of gas in the supply pipe be cut off for any

reason and the burner not supplied with gas, the flame of the burner would be extinguished and then if the supply of gas is again continued there would be danger of the escape of gas from the burner.

55 This invention provides for means whereby the control valve 11 will be closed whenever the supply of gas to the distributing pipe is interrupted. To effect this cutting off of the control valve a thermostatic bar 14 is carried on a bar 15 which is adjustably mounted at 9 on a bracket 16 which in turn clampingly engages the distributing pipe 12.

Bracket 16 is secured to the distributing pipe by means of a bolt 17 which may be loosened 60 so that 16 can be rotatably or longitudinally adjusted thereon. The thermostatic bar 14 is shown in substantially a U-shape with its outer end normally contacting a terminal member 18 which is carried by and insulated

65 from the bar 15 by means of insulating members 45 and 46. Positioned adjacent thermostatic bar 14 is a perforation 19 in the distributing pipe 12 which is of sufficient size to permit the escape of gas therefrom so that 70

when lighted it will raise the temperature of the thermostatic bar sufficiently to cause the same to be distorted so that its contact with the terminal 18 will be broken. It is apparent 75 that other types of thermostatic controls

70 might be used in place of the bar.

80 Control valve 11 consists of a body member 20 having an inlet opening 21 which communicates with the supply pipe 10 and an outlet opening 22 which connects with the distributing pipe 12. A valve seat 23 is positioned in 20 intermediate 21 and 23 and is provided with a valve 24 which is adapted to cooperate therewith to control

85 the flow of gas from said supply pipe to said distributing pipe. Valve 24 is provided with a slidably mounted valve stem 25 which is rigidly attached thereto and extends without the body member 20. An externally threaded sleeve 26 fits over the

90 valve stem 25 and is threaded into body member 20 at 27. To secure said sleeve against accidental movement relative to 20, a lock nut 28 is provided. Intermediate 95 the lower end of sleeve 26 and the upper 100

side of valve 24 is interposed a compression spring 29 which serves to normally maintain said valve in the closed position.

To maintain the valve 24 in the operative open position a nut 30 having oppositely disposed ears 31 is threaded onto the outer end of stem 25 and secured against accidental displacement by means of lock nut 32. A U-shaped member 33 having eyelets 34 at its opened ends engages ears 31 and extends downwardly at an angle to stem 25 so that the closed end thereof rests against the upper side of a horizontally disposed lever 35 which is pivotally mounted at 36 to a stationary plate 37 carried by body member 20. A lip 38 is formed integral with lever 35 and serves as an abutment for 33 so that as the lever 35 is moved to the position shown in Figs. 1 and 2, 33 will securely hold the valve in the open position against the action of the spring 29. Catch 40, pivoted as at 41, has a notch 42 formed therein to engage upturned flange 43 on lever 35 when the valve parts are holding the valve 11 in open position. Coil 44, being positioned as shown in Fig. 2, causes catch 40 to release lever 35 when coil 44 is energized, whereby member 33 swings out and permits spring 29 to move stem 25 longitudinally to cut off the flow of gas through pipes 10 and 12. A stop 39 positioned on plate 37 serves to limit the outward movement of lever 35 but will not prevent the proper closing of the valve 24.

Positioned on plate 37 is a signal light 47 and a switch 48 which will be further described.

Referring to Fig. 5, which shows a diagrammatic view of the electric circuit, 49 and 50 are the ordinary supply wires connected with a suitable electrical source not shown. A wire 51 connects wire 49 with thermostatic bar 14 and the wire 52 having a switch 48 connects the wire 50 with the signal light 47. Wire 53 connects the opposite side of light 47 with coil 44 while the opposite side of coil 44 is connected with terminal 18 by means of wire 54. The flame F from distributing pipe 12 produces a sufficient heat to distort thermostatic bar 14, thus causing a gap between said thermostatic bar and terminal 18 to open the circuit. When the flame F is extinguished due to the cutting off of the supply of gas to distributing pipe 12, 14 will move downwardly and close the circuit. It will be noted that all of the electrical appliances in this circuit are in series, therefore when the circuit is closed the light 47 will be illuminated and the coil 44 will be energized, thereby releasing lever 35 and permitting the spring 29 to close valve 24 so that, should the gas again enter the supply pipe 10, no gas could pass into the distributing pipe 12.

It is apparent that a small burner of some special construction might be provided to communicate with perforation 19 and furnish the flame to heat the thermostatic control.

I do not wish to limit this invention to the structure shown and described as many modifications might be made within the scope of the appended claims without departing from the spirit thereof.

What I claim is:

1. In a cut-off device for gas service a supply pipe, a distributing pipe, a vertically reciprocating control valve operable to regulate the flow of gas from said supply pipe to said distributing pipe, a burner communicating with said distributing pipe, an auxiliary burner remotely positioned relative to said first named burner communicating with said distributing pipe, a thermostat responsive to the heat of said auxiliary burner, means for releasably holding said control valve in the open position mounted for independent swinging movement on the upper end of said valve, and electrically controlled means controlled by said thermostat operable to release said releasable holding means to permit the closing of said control valve when the flow of gas in said distributing pipe is interrupted and said auxiliary burner no longer heats said thermostat.

2. In a cut-off for gas service, a supply pipe, a distributing pipe, a burner communicating with said distributing pipe, and a control valve interconnecting said supply pipe and the distributing pipe, said control valve being operable to control the flow of gas from said supply pipe to the distributing pipe and comprising a vertically reciprocating stem, a spring tending to maintain the valve closed, a member swingably mounted at its one end to said stem, a releasable lever pivotally supported for horizontal movement toward and from said stem, said lever engaging the free end of said swingable member to hold the control valve open an auxiliary burner in communication with said distributing pipe, and thermostatically operated means to releasably hold the said lever in such position responsive to the heat of said auxiliary burner including a catch and means to release said catch when the said thermostat is in the predetermined position.

3. In a cut-off for gas service, a supply pipe, a distributing pipe, a main burner and an auxiliary burner in communication with said distributing pipe, a thermostatic switch responsive to the heat of said auxiliary burner, an electromagnetic coil energized by the closing of said switch, and a control valve interconnecting said supply pipe and distributing pipe comprising a vertically disposed, longitudinally reciprocating valve

stem, a spring to urge said valve stem toward closed position, a depending member swingably mounted at its one end to said stem, a releasable lever pivotally supported for horizontal movement toward and from said stem to engage the free end of said depending member, and a catch movable by said coil to release said lever from effective engagement with said depending member when said thermostatically controlled switch is closed.

In testimony whereof, I hereunto affix my signature.

JOSEPH A. SICKELS.
